UNITED STATES PATENT OFFICE.

THOMAS COOPER ALLISON, OF DOVER, OHIO, ASSIGNOR OF ONE-HALF TO DAYTON E. DOWNEY, OF HIGHLAND PARK, MICHIGAN.

AUTOMATIC STEAK BEATER.

Application filed February 9, 1925. Serial No. 7,952.

This invention aims to provide a simple machine for operating on beef steak or meat, to render the meat tender, without pounding it, the machine being so constructed that it may be taken apart readily for cleaning.

It is within the province of the disclosure to improve generally and to enhance the utility of devices of that type to which the invention appertains.

Although a preferred form of the invention has been shown, it will be understood that a mechanic, working within the scope of what is claimed, may make changes and alterations without departing from the spirit of the invention.

In the accompanying drawings:—

Figure 1 shows in elevation, a device constructed in accordance with the invention, parts being broken away; Figure 2 is an elevation wherein the device is viewed endwise; and Figure 3 is a perspective view showing the bearing.

In carrying out the invention, there is provided a U-shaped frame 1 including a base 2 and standards 3, the standards being inclined so that they project beyond the base 2. Through the instrumentality of a clamp 4, or the like, on the base 2, the frame 30 1 may be mounted on a gable or bar.

The standards 3 are supplied with longitudinal guide slots 5. In the upper edges of the standards 3, openings 6 are fashioned, the openings communicating with the guide slots. The numeral 7 marks a main or upper roller, having trunnions 8 which are journaled in the guide slots 5 at the upper ends thereof. A crank 9, or any other suitable device, mounted on one of the trunnions 8, constitutes means whereby the main roller 7 may be rotated. The numeral 10 designates an auxiliary or lower roller, the trunnions 11 of which are journaled in the guide slots 5 of the standards 3 below the openings 6.

H-shaped bearings 12 are supplied and slide in the guide slots 5, the bearings being equipped in their ends with notches 14 which receive the standards 3 on each side of the guide slots 5. The H-shaped bearing 12 is supplied with a depending boss 15, and in the upper surface of each bearing 12 there is a seat 16 wherein the trunnion 11 of the auxiliary roller 10 is journaled. There is a boss 17 on each standard 3 at the lower end

of the corresponding guide slot 5. Compression springs 18 are located in the guide slots 5, the upper ends of the springs being engaged with the bosses 15 of the bearings 12, and the lower ends of the springs 18 being engaged with the bosses 17 of the standards 3. The rollers 7 and 10 are provided with teeth 19 or any other suitable elements adapted to operate on the steak or other meat. The diameter of the rollers 10 and 7 is such that, when the rollers are in engagement with each other, under the pressure of the springs 18, the trunnions 11 of the auxiliary roller 10 are so disposed that they cannot pass out through the openings 6 in the standards 3. The machine, therefore, will not fall apart when it is not in use. When it is desired to take down the machine for cleaning, the auxiliary 10 is crowded downwardly, the springs 18 being compressed. Then, the main roller 7 may be removed, the trunnions 8 of the main roller passing outwardly through the openings 6. Then, the auxiliary roller 10 may be permitted to move upwardly, the trunnions 11 of the auxiliary roller passing outwardly through the openings 6. Finally, the bearings 12 and the springs 18 being removed, the machine being knocked down so that it may be washed.

In practical operation, the roller 7 is rotated by means of the crank 9, and the meat is drawn between the rollers 7 and 10, and is worked back and forth until tender, the roller 10 moving downwardly, depending upon the thickness of the meat. The springs 18 press the roller 10 against the under surface of the meat, and cause the meat to be pinched firmly between the rollers 7 and 10, the roller 10 being rotated by the meat, as the meat moves back and forth, responsive to the rotation of the main roller 7.

Having thus described the invention, what is claimed is:—

A meat tenderer comprising standards having elongated slots, the standards being provided in their forward edges with openings which communicate with the slots, an upper roller having trunnions journaled in the standards at the upper end of the slots and above the openings, a lower roller having trunnions journaled in the slots and located below the openings, the roller being of such diameter that when they are in contact, the trunnions of the lower

roller cannot escape through the openings, means for rotating the upper roller, and springs located in the lower ends of the slots and cooperating with the trunnions of the 5 lower roller to raise the lower roller toward the upper roller, the springs being compressible to permit the trunnions of the upper roller to be moved outwardly through the 10 openings, and then to permit the trunnions of the lower roller to be moved outwardly through the openings, the rollers being independently removable in the order speci-

fied, the standards being backwardly inclined with respect to the vertical, whereby the trunnions of the upper roller will ride 15 on the rear edges of the slots and tend to prevent the trunnions of the upper roller from escaping through the openings whilst the meat is being removed and when the rotating means for the upper roller is released. 20

In testimony that I claim the foregoing as my own, I have hereto affixed my signature.

THOMAS COOPER ALLISON.
